UNITED STATES PATENT OFFICE.

BENJAMIN E. D. STAFFORD AND ETHAN I. DODDS, OF PITTSBURGH, PENNSYLVANIA,
ASSIGNORS TO FLANNERY BOLT COMPANY, OF PITTSBURGH, PENNSYLVANIA.

FLEXIBLE STAY-BOLT.

1,201,988.

Specification of Letters Patent. Patented Oct. 17, 1916.

Application filed March 27, 1915. Serial No. 17,521.

To all whom it may concern:

Be it known that we, BENJAMIN E. D. STAFFORD and ETHAN I. DODDS, citizens of the United States, and residents of Pittsburgh, in the county of Allegheny and State of Pennsylvania, have invented certain new and useful Improvements in Flexible Stay-Bolts; and we do hereby declare the following to be a full, clear, and exact description 10 of the invention, such as will enable others skilled in the art to which it appertains to make and use the same.

Our invention relates to an improvement in stay bolts for boilers, the object being to 15 provide a yielding coupling for one end of the bolt, whereby the latter will be free to follow the movements of the fire box sheet of the boiler without buckling or unduly straining either of the sheets, thus equalizing 20 the stresses on both sheets.

A further object is to so construct the bearing for the bolt head as to prevent scale from getting between the bolt and the part 25 of the bearing directly supporting the bolt head.

With these objects in view our invention consists in the parts and combination of parts as will be more fully explained and pointed out in the claims.

30 In the accompanying drawings, Figure 1 is a view partly in section and partly in elevation of our improvement, and Figs. 2 to 4 inclusive are views in section of modifications.

35 A represents a rigid bolt one end of which is secured by threads directly to the inner sheet 2 of the fire box or boiler, and the other end threaded for the attachment of the head 3.

40 4 is a sleeve adapted to be screwed into the outer sheet and provided internally with the flat, annular, inwardly projecting seat 5, and at its inner end with the curved or inclined seat 6, the seat 5 forming a support 45 for the outer enlarged end 8 of the bushing 7 and the curved seat 6 forming a rest for the inner end 9 of said bushing. This bushing is cylindrical in shape and hollow, for the passage of the bolt through the same, 50 and the portion thereof between its ends is fluted circumferentially as shown, so as to act as a spring which will yield or give under longitudinal or lateral stresses to which the bolt may be subjected.

55 The bushing is provided at its outer end

with a curved seat 10 in which the head 3 of the bolt 1 normally rests, and the inner end of the said bushing is constructed to bear against a shoulder 11 formed on the bolt, and extending completely around the same. In 60 the present instance this shoulder 11 is inclined, and the inner end of the bushing is similarly shaped so as to make a close fit with the bolt to prevent the passage of any scale up into the space between the bushing 65 and bolt, and as the enlarged end 8 of the bushing makes a close fit with the seat 5 in the sleeve, no scale can pass around the outside of the bushing, consequently there is no chance for scale to reach either the head 3 70 or its seat 10 in the bushing. The bushing 7 is held in place on its seats 5 and 6, by the cap 12 screwed onto the outer end of the sleeve and provided with an inwardly projecting annular lip 13 which bears on the 75 outer end of the bushing and holds same firmly on its seat 8.

With this construction it will be seen that in pulling stresses on the bolt, the head 3 thereof rests solidly on the unyielding seat 80 10 and acts as an ordinary flexible bolt of the Tate type.

When the bolt elongates or is forced outwardly due to movements of the inner sheet, the shoulder 11 bearing against the inner 85 end of the bushing compresses the latter sufficiently to compensate for the movement, and when the stress is relieved the spring action of the fluted bushing forces the bolt back to its normal position.

90 The construction shown in Fig. 2 is substantially like that of Fig. 1 except that the lower end of the fluted bushing is connected to the bolt by screw threads; the upper end of the bushing is flush with the sleeve, thus 95 doing away with the long annular lip 13, and the head of the bolt is formed as an integral part of the bolt.

In Fig. 3, the lower end of the bushing is connected by threads with the bolt shank, as 100 in Fig. 2, and the head of the bolt has a threaded engagement with the bolt as in Fig. 1.

105 In the construction shown in Fig. 4, which is particularly adapted for the fire sheet of a boiler, the sleeve 4^a is screwed into the sheet and its outer edge upset against the outer face of the sheet so as to positively lock the sleeve against inward displacement and also form a tight joint.

The bushing 7^a is provided at its outer end, which is closed, with external threads which engage internal threads in the sleeve, thus locking the outer end of the bushing to the sleeve against movement, except of course the turning movement which is necessary in assembling the parts. The bushing is provided adjacent its inner end with a shoulder 9^a which normally rests on the annular seat 6^a formed at the inner end of the sleeve, and the portion of the bushing intermediate its shoulder 9^a and threaded outer end, is fluted so as to provide for the necessary spring action. The inner end of the bushing passes through the sleeve and is internally threaded for the attachment of the bolt 1^a. With this construction it will be seen that a pulling strain on the bolt simply draws the shoulder 9^a onto its rigid unyielding seat 6^a, the shoulder 9^a forming a head on which the bolt may turn so as to accommodate the latter to the movements of the sheets, whereas an outward movement of the fire sheet, or a collapsing movement of the two sheets, causes the fluted part to give or yield and thus absorb the shock or strains.

The spring bushings or inner sleeves are preferably heat treated and cooled in oil so that the convoluted or spring section thereof will retain its elasticity when exposed to the high temperatures to which they are subjected in use. By increasing the number of convolutions, sufficient elasticity may be produced to absorb or take care of all necessary longitudinal, lateral and vibratory movements to which the bolt may be subjected, due to elongation of the bolt itself, or to longitudinal and lateral movements of the bolt due to outward or lateral movement or buckling action of the inner sheet, and provides in effect for universal movement of the end of the bolt within the coupling.

It is evident that many slight changes might be resorted to in the relative arrangement of parts shown and described without departing from the spirit and scope of our invention. Hence we would have it understood that we do not wish to confine ourselves to the exact construction shown and described, except as required by the scope of the appended claims.

Having fully described our invention what we claim as new and desire to secure by Letters-Patent, is:—

1. In stay bolt construction, the combination of a sleeve, a spring bushing within the sleeve and secured at one end to the latter and a bolt engaging the free end of said spring bushing whereby a movement of the

bolt in one direction compresses the spring bushing.

2. In stay bolt construction, the combination of a sleeve, a spring bushing within the sleeve and supported at both ends within and by the sleeve, and a bolt engaging said bushing at one end, whereby longitudinal movement of the bolt toward the sleeve will compress the bushing.

3. In stay bolt construction, the combination of a sleeve, a spring bushing within the sleeve, the said bushing being secured at one end to the sleeve and loosely supported thereby at its other end, and a bolt engaging the free end of the bushing whereby the latter may be compressed by a movement of the bolt in one direction.

4. In stay bolt construction, the combination of a sleeve and a spring bushing within the sleeve, the said bushing being detachably secured at one end to the sleeve and supported by said sleeve at its other end against expansion, and a bolt having engagement with the free end of the bushing whereby the latter may be compressed by a movement of the bolt in one direction.

5. In stay bolt construction, the combination of a sleeve and a spring bushing within the sleeve and secured at one end to the latter, and a bolt the head of which is mounted in a curved seat at the fixed end of the bushing and engaging the bushing at the free end of the latter.

6. In stay bolt construction, the combination of a sleeve, a spring bushing within the sleeve, one end of the bushing being rigidly secured to the sleeve and the other end movably supported by the latter, and a bolt having a head resting within a curved seat in the fixed end of the bushing and having a shoulder bearing against the free end of the latter.

7. In stay bolt construction, the combination of a sleeve having two internal seats, a spring bushing the ends of which rest on said seats, a cap for locking the outer end of the bushing to the sleeve, and a bolt the head of which rests within a curved seat in the fixed end of the bushing and is provided with a shoulder bearing against the free end of said bushing.

In testimony whereof, we have signed this specification in the presence of two subscribing witnesses.
